NOTE COMPANY, OF NEW YORK, N. Y., A CORPORATION OF NEW YORK

NUMBERING HEAD

Application filed January 11, 1929. Serial No. 331,762.

The invention relates to numbering heads, and more particularly to a numbering head in which the digit wheels of the lower denominations receive a timely positive actuation by mechanisms incorporated in the numbering machine proper, as distinguished from that type of numbering head including therein transfer mechanisms through which power is transmitted from, or as a result of the actuation of, a digit wheel of lower denomination to a digit wheel of higher denomination.

Heretofore, it has been the common practice to construct numbering heads in which the actuation of the various digit wheels is determined solely by a mechanism or mechanisms actuated or controlled by a digit wheel or wheels of lower denomination than the wheel to be actuated.

The numbering heads most extensively used have included therein a swing frame carrying a spring pressed multiple toothed pawl, known as a comb pawl, the teeth of which are of progressively decreasing length, and are adapted to enter sockets or recesses in the digit wheels respectively, or in a ratchet wheel secured thereto. Acting upon the several digit wheels were a plurality of spring pressed detent or holding and alining pawls. The swing frame carrying the comb pawl was actuated by a plunger which was depressed upon engagement with the tympan of the impression cylinder or a striker member so as to tension the springs acting upon the plunger and develop sufficient energy therein to provide the power necessary to turn one or more of the digit wheels according to the setting of the comb pawl. This extensively used type of numbering head required the cutting of the inking rollers of the numbering machine by which the digit wheels were inked, since the actuating plunger, to permit the development of energy in the springs acting thereon by the tympan or platen of the impression cylinder or the striker member, was required to project considerably beyond the printing surface of the characters upon the digit wheels. In this old type of numbering head, various automatically acting safety locks were used as to

each digit wheel to avoid possible improper turning of wheels for various reasons.

Furthermore, the springs acting upon the plunger were subjected to a varying load according to the number of wheels to be turned thereby.

When numbering heads of the type above referred to were used in connection with bank notes, bonds, stocks and other negotiable instruments, wherein a possible duplication of numbers involved great wastage of time and material, great care had to be exercised, during the operation of a numbering machine fitted with such heads, to quickly detect any failure of the numbering heads as a result of breakage of any of the numerous springs upon which the perfect actuation of the head was dependent.

Numbering heads, differing in construction from those above referred to, as to the actuating mechanism and the transfer mechanism, have been used, but all such numbering heads, irrespective of the type, have contained a single actuating member through which power was directly or indirectly applied to all of the digit wheels embodied in the numbering head. Furthermore, all such numbering heads embodied a number of springs operative upon different parts of the head, upon which springs the accurate actuation of the digit wheels, and alinement of the printing characters upon the digit wheels, was dependent.

With the above conditions in mind, I have produced a numbering head in which there are no springs acting directly or indirectly upon the various digit wheels, nor upon the mechanisms actuating same, thus ensuring positive movement of the various digit wheels and avoiding a possible failure of their progressive actuation.

In the numbering head of the invention, each of certain of the digit wheels of lower denomination is provided with its own actuating member, co-operating with a member forming a part of the numbering head machine itself. Each of these digit wheels thus receives a timely, direct actuation from a source of power, by a mechanism independent of that acting upon other digit wheels, the

movements of each wheel not being caused or controlled in any way by the movements of the adjacent wheel. This utilization of independent means for the actuation of the wheels of lower denomination, not only avoids the necessity for the employment of transfer mechanisms of any kind as to these wheels, but precludes possibility of the failure of any wheel to be properly turned as required because of the breakage, or loss of adjustment, of delicate mechanisms in the numbering head itself.

A great advantage of a numbering head embodying the invention is that notwithstanding the necessity for great compactness in its structure, and the necessity for the use of more or less light delicate parts to secure this compactness, the proper functioning of the head is not dependent upon light delicate mechanisms, and the head as a whole may be made very strong and rugged.

With the class of work for which the numbering head of the invention is particularly designed, a plurality of longitudinally extending rows of numbering heads are used upon the cylinder of the numbering machine, and the numbering heads of each row are required to be not only in alinement with each other, but capable of adjustment longitudinally of the cylinder to secure the spacing of different units of each row in relation to each other, to properly position the numbers with regard to their relative location on a previously printed sheet upon which the numbers are to be impressed.

In view of this condition, the numbering head of the invention is so constructed that a plurality of alined units may be incorporated in the same numbering head construction, the digit wheels of each unit being actuated by the same mechanism operative upon the corresponding digit wheels of the other units, each of the units being adjustable in relation to said actuating means and to each other for the purpose of securing the longitudinal adjustment thereof above referred to. Furthermore, the numbering head as a whole may be adjusted circumferentially of the numbering head cylinder of the machine to secure a proper spacing of each row of numbering head units in relation to other rows.

The various digit wheels of each unit all rotate about the same axis, and while it is possible with one of the wheels to have the actuating mechanism co-axial therewith and act directly thereon, with the other positively actuated wheels it is necessary that they be actuated indirectly by an actuating mechanism not concentric with the axis of the digit wheels actuated thereby. The reason for this will appear more fully hereinafter.

The utilization of independent actuating means for corresponding digit wheels of different units of the numbering head permits,

if desired, the use of two closely adjacent parallel rows of digit wheels in each unit, and the simultaneous actuation of the digit wheels of each row of the same denomination by the same actuating mechanism, thus permitting close spacing of the numbers impressed upon the sheet, not only because of the close juxtaposition of the digit wheels in the parallel rows of each unit, but of the bringing of adjacent numbering heads, into such close relation as to secure the proper position of all of the numbers throughout even a large sheet of paper.

It is the common practice, in the class of work for which the numbering head of my invention was produced, to limit the run of a machine to one thousand sheets with each setting of the numbering head units, and then to reset all of the numbering heads for a succeeding run. With this condition, it is only necessary to provide an actuating mechanism for the units, tens and hundredths digit wheels, and to have the thousandths wheel automatically actuated by a transfer mechanism. Consequently, I incorporate in each unit, a transfer mechanism actuated by the hundredths wheels and operative upon the thousandths wheel of that unit. The wheels above the thousandths wheel in denomination are actuated only when setting the head, which is hand work. I provide, in each numbering head unit, however, a manually operable lock which may be released to permit the hand setting of wheels of denomination above a thousand, and set to hold such wheels against rotation after they have once been properly set. This is permissible since the automatic actuation of such wheels is not required in the operation of the machine.

Prior to each run of the machine, it is always necessary to set the various thousandths wheels by hand; and to permit a rapid setting of such wheels, I so construct and position the transfer mechanism by which power is applied to the thousandths wheel through the hundredths wheel shaft, as to make the mechanism inoperative in a manner to permit the turning of the thousandths wheels independently of this mechanism and restore the parts to their normal operative relation after the hand setting of the thousandths wheel.

Since, under some conditions, it may be necessary to hand set digit wheels of a denomination below the thousandths wheel, I so construct the actuating mechanism for each of these wheels as to permit the disconnection of the actuating mechanism from the source of power to facilitate such hand setting of such digit wheels, the means employed being readily accessible so that the digit wheel actuating mechanism may be reconnected with the source of power following the hand setting of the wheels.

I also provide in the numbering head a

straightening bar operative upon the automatically actuated digit wheels of each unit to bring all of the digit wheels of the unit into proper accurate alinement following the actuation of such digit wheels or any of them.

While digit wheels of corresponding denomination in the different units of each numbering head receive movement from the same actuating member, each unit is so constructed that the positively actuated digit wheels of each unit may be adjusted in relation to its actuating member so as to permit the characters thereon to be brought into proper alinement with the characters upon other digit wheels of the same unit.

Each numbering head is so constructed that it may be quickly and conveniently mounted upon, or removed from, the numbering head cylinder to facilitate the makeready of the numbering machine and changes in the makeready, according to the requirements of the work to be done upon the numbering machine.

The invention consists primarily in a numbering head embodying therein a bridge, means whereby said bridge may be mounted upon a numbering head cylinder, a plurality of shafts rotatably mounted in said bridge, gears carried by said shafts respectively, a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, said sleeve, gears carried by said independently rotatable wheels, and a gear carried by each of the other of said sleeves, entrained with a gear upon an independently rotatable wheel; and in such other novel features of construction and combination of parts, as are hereinafter set forth and described and more particularly pointed out in the claims hereto appended.

Referring to the drawings,

Fig. 12 is a side elevation, showing in detail the straightening mechanism; and

Fig. 13 is a plan view of the mechanism shown in Fig. 12.

Like numerals refer to like parts throughout the several views.

In the embodiment of the invention shown in the drawings, the numbering head cylinder is shown at 20, and the numbering head actuating gears forming a part of the numbering machine are shown at 21, 22 and 23 respectively. The mechanism for operating these gears is not herein shown, since such is a part of the numbering machine and not of the numbering heads used thereon. It is necessary, however, for a proper understanding of the mode of operation of the numbering head, to explain that these gears 21, 22 and 23, throughout the major portion of each rotation of the cylinder 20, rotate with said cylinder, but that following the completion of the printing operation by all of the numbering heads upon the cylinder, and prior to the succeeding inking operation, these gears 21, 22 and 23, as required for the progressive actuation of the various numbering heads, have rotary movement independently of the cylinder 20 to the extent of one tooth, so as to simultaneously impart a one-tenth revolution to the various digit wheels actuated therethrough. The gear 21 receives such an impulse with each revolution of the cylinder 20; the gear 22 receives such an impulse upon each tenth revolution of said cylinder, and the gear 23 receives such an impulse upon each one-hundredth revolution of said cylinder.

The numbering machine itself is a specially constructed machine, and the numbering heads made the subject matter of this application are adapted for use only with a machine in which gears such as 21, 22 and 23 are operated in the manner above described.

The numbering head proper embodies therein a bridge member 24, having end brackets 25 and 26, one or both of which is removable in relation to said bridge to facilitate the assembly of the numbering head and a change in the number of units embodied therein, as required. This bridge is provided with a depending rib 27 adapted to bear upon an intermediate rim 28 upon the cylinder 20, for the purpose of affording support for the

bridge at a point or points intermediate the ends thereof.

The ends of the cylinder 20 are provided with an overhung circumferentially extending bevel 29, as shown, which co-operates with 5 means for securing the bridge 24 in relation to said cylinder while permitting its adjustment circumferentially thereof.

Co-operating with the bridge member 24, 10 and with the bevel 29, is a bevelled dog 30 having a screw threaded opening therein engageable by the screw threaded rod 31. Slidably mounted on said rod is a dog 32 similar to the dog 30 and acted upon by a collar 15 33 upon said rod 31. By using the dogs 30 and 32, slidable in relation to the bridge 24, considerable manufacturing difficulties may be avoided, so far as providing a proper bearing for the rod 31 is concerned. The dogs 30 20 and 32 have a dovetail fit with the bridge 24, and the rod 31 is provided with an operating head 34.

While the end brackets 25 and 26 are not made integral with the bridge 24, they nevertheless 25 form a part of this bridge structure and are removable therewith.

Mounted in the brackets 25 and 26 of the bridge 24 are three shafts 35, 36 and 37 which are so positioned as to permit the gears 38, 39 30 and 40 carried thereby respectively to mesh with the gears 21, 22 and 23 of the numbering machine. Each of these gears 38—39—40 has ten teeth so that the shafts carrying same receive one-tenth of a revolution with each 35 actuation of the gears 21, 22 and 23.

The top of the bridge 24 is undercut, as shown in Fig. 4, to permit a numbering head unit or units to be firmly mounted thereon and secured thereto while at the same time 40 permitting adjustment of each unit longitudinally of the bridge 24 and of the cylinder 20.

Supported by the bridge 24 is one or more numbering head units, each of which is an exact replica of every other, so that a detailed 45 description of but one of these units is necessary. The number of aligned numbering head units in each head and their spacing in relation to each other, longitudinally of the bridge 24, is determined solely by the character of work required, as is the number and arrangement of the numbering heads upon the cylinder 20.

In the accompanying drawings, Figs. 1 and 55 2, a numbering head is broken away and condensed so as to show only two of these units.

Each of the numbering head units comprises a frame 41 having rotatably mounted therein three sleeves 42, 43 and 44, adapted 60 respectively to receive one of the shafts 35, 36 and 37 with which they are connected by a spline or feather so as to permit the frame to be moved longitudinally of said shafts. The base of the frame 41 is undercut, as shown 65 particularly in Fig. 4, so as to permit it to

dovetail with the undercut top of the bridge 24, thus holding the unit firmly in position upon the bridge while permitting it to be moved longitudinally thereof, when required to secure the proper spacing of the units in 70 relation to each other and to the designs upon the previously printed sheet.

The digit wheels proper, for a single number, are carried by, and co-axial with, one of the sleeves, as 42 in the drawings. One 75 of these digit wheels as 45, the units digit wheel, is keyed or otherwise secured to said sleeve, the tens wheel 46, the hundredths wheel 47, the thousandths wheel 48 and the wheels 49 of higher denomination being idly mounted 80 upon said sleeve.

While the invention is particularly adapted to the use of two parallel rows of digit wheels, when the conditions require the numbers to be positioned fairly closely together, 85 I will describe first the construction employing but a single set of digit wheels and the mechanisms for actuating same, since with a twin head, the operation of the second set of digit wheels is merely a matter of the use 90 of intermediate gears connecting the digit wheels of one set with the corresponding digit wheels of the other set, or the association with certain gear wheels of a digit wheel carried by and rotatable therewith. This will appear more fully hereinafter.

Each of the digit wheels 45, 46 and 48 carries a gear 50, the digit wheel 47 carrying two such gears. These gears serve as spacers between the digit wheels and between the units 100 digit wheel and one end of the frame 41, as well as a power receiving element as to the wheels 46, 47 and 48, and power transmitting means as to the wheel 45, for causing the actuation, when desired, of the other units 105 wheel of a twin head.

The units digit wheel, being connected to the sleeve 42, will receive one-tenth of a revolution with each impulse imparted to the shaft 35 by the gears 21 and 38. It is obvious, 110 however, that this shaft cannot be utilized for turning the wheels 46, 47 and 48. Consequently, I secure to the sleeve 43, a gear wheel 51 so that this gear wheel will receive one-tenth of a revolution with each impulse 115 of the shaft 36 by the gears 39 and 22. Since the gears 50 and 51 must be of smaller diameter than the digit wheels to permit the inking and the making of an imprint by said wheels, I transmit motion from the gear 51 to the digit wheel 46 through an intermediate gear 52 idly mounted upon the sleeve 44, which gear 52 is enmeshed with the gear 50 carried by said tens wheel 46. It is obvious that the gear 51, through the sleeve 43 and shaft 36, acts solely to rotate the tens wheel 46. The gears 51 and 52 each have ten teeth.

The hundredths wheel 47, as stated, carries two gears, but this is largely a matter of convenience and strength. While this wheel 120

47 is, like the wheel 46, idly mounted upon the sleeve 42, it is actuated by means of twin gears 53 carried by and rotatable with the sleeve 44, which in turn is connected with the shaft 37, so that the hundredths wheel 47 receives one-tenth of a revolution with each impulse of said shaft 37 by the gears 40 and 23. The gears 53, however, instead of transmitting power through an intermediate gear to the hundredths wheel 47, are directly enmeshed with the gears 50 carried by that wheel. It is thus obvious that the hundredths wheel will receive one-tenth of a revolution with each impulse of the shaft 37 by the gears 40 and 23. Hence the units, the tens and the hundredths wheels are each actuated by their own independent shaft; the progressive actuation of such wheels is determined by the functioning of the gears 21, 22 and 23 of the numbering machine, and no transfer mechanisms whatever are employed, nor is there any transfer mechanism between the hundredths wheel 47 and the thousandths wheel, which is also mechanically actuated as required during the progressive actuation of the various digit wheels.

This thousandths wheel 48, however, is also actuated from the shaft 37 through a Geneva stop movement consisting of a driving single-toothed gear 54, having a fall 55 therein for receiving one arm of a rocking lock lever 56, the other arm of which engages the teeth of a ten-tooth gear 57 carried by a sleeve 58 mounted in the frame 41 below the sleeve 44. The gear 57 is idly mounted upon the sleeve 58, being connected therewith by a clutch member 59 which may be released at will in a manner, and for the purposes, hereinafter described, in connection with the mechanisms provided by which the various numbering head units may be quickly set preparatory to a run of the numbering machine.

For the moment, the clutch member 59 will be considered merely as a means of connecting the gear 57 to the sleeve 58 for transmitting power from the shaft 37 to the thousandths wheel 48.

The sleeve 58 carries a gear 60 rotatable therewith and meshed with a gear 61 idly mounted upon the sleeve 44, which gear in turn is enmeshed with the gear 50 of the digit wheel 48.

The remaining wheels 49, which may be of any desired number, are merely idly mounted upon the sleeve 42 with suitable spacers separating them, these wheels always being hand set and never being automatically actuated.

It will be noted that the tens, the hundredths and the thousandths wheels of each unit are actuated by gears, either fixedly or idly mounted upon the sleeve 44, so that these gears may be used for alining or registering the various wheels actuated thereby so as to

ensure a proper alinement of the printing characters following each actuation of the unit. In order to have this alining mechanism also act upon the units wheel, I idly mount, upon the sleeve 44, a gear wheel 62 enmeshed with the gear 50 of the units wheel 45.

Heretofore, I have described merely the combination and relation of parts for a numbering head unit having a single set of digit wheels. If it be desired to have two sets of such digit wheels, however, I mount upon the sleeve 43, which is parallel with the sleeve 42, a units digit wheel 45a, a tens digit wheel 46a secured to and rotatable with the gear 51, a hundredths wheel 47a, a thousandths wheel 48a and wheels 49a of higher denomination. Each of the wheels 45a, 47a and 48a will have secured thereto a ten-toothed gear 50a, the wheel 47a having two such gears.

The gear of the wheel 45a will mesh with the gear 62, so that this wheel will be driven from the sleeve 42; the gear 46a will be driven directly from the sleeve 43; the wheel 47a will be driven from the twin gears 53 in the same manner as the wheel 47, while the gear of the wheel 48a will be meshed with the gear 61 so as to be driven the same as the digit wheel 48.

With a twin unit, the mechanisms for alining or registering operate upon both sets of wheels in exactly the same manner as though there were only a single set of wheels in the head, since the power for operating the wheels of both sets is transmitted through exactly the same mechanisms, excepting as to the units and tens wheels, wherein, as to the former, there is an intermediate gear transmission, and as to the latter, there is a direct drive by a sleeve instead of through an intermediate transmission.

While the thousandths wheel or wheels are actuated through a Geneva stop movement as described, this mechanism is not actuated as a result of the turning of the hundredths wheel, but merely as a result of the turning of the power shaft for actuating the hundredths wheel. Furthermore, the members of the Geneva stop mechanism are arranged exteriorly of the frame 41 where there is ample space for providing a strong structure. While the various gears carried by the wheels and the intermediate gears are of necessity fairly thin, it will be noted that the gears and wheels are practically the only mechanisms contained between the ends of the frame 41, and that there are no other moving parts or springs acting in conjunction with these gears or wheels for imparting motion to any of the wheels, or for retarding the rotary movement thereof.

Ordinarily, in the class of work for which the numbering head of the invention is particularly designed, sheets are printed in lots of one thousand for each run of the press,

and upon the completion of this run, the numbering head is reset preparatory to the succeeding run of one thousand sheets. It is therefore highly desirable that means be provided, in connection with each unit, permitting the disconnection of the thousandths wheel from the means transmitting power thereto so as to permit the quick resetting of the thousandths wheel. Since the wheels 49

5 above the thousandths in denomination are always hand set, the means about to be described apply only to the thousandths wheel. In fact throughout the construction of the numbering head, the wheels of different denominations in each unit, and their actuating means, are characterized by complete independence, one of the other, in all of their functions, the proper timing in their operation being under the control of mechanisms

10 in the numbering machine and not in the head units themselves.

Referring first to the release mechanism for the wheel or wheels 48, the thousandths wheels, this is done by means of the clutch mechanism connecting the driven gear 57 of the Geneva stop movement with the sleeve 58 by a mechanism which may be actuated by an ordinary hand tool, such as a screw driver, in a manner to disconnect this clutch and keep it

15 open until the thousandths wheel or wheels have been properly set. This clutch mechanism comprises a rod 63 slidably mounted in the sleeve 58, and carrying, at one end thereof, a pin 64 slidable in slots formed in the end of said sleeve 58. The gear 57 is castellated, the pin 64 being adapted to enter between the projecting teeth of said gear. The other end of said rod 63 is enlarged as shown at 65, and reduced to a point, the sleeve 58 being

20 shouldered as shown, so as to form a seat for a spring 66 acting between the shoulder therein and the enlarged head 65 of the rod 63. The tendency of this spring is to normally engage the pin 64 with the gear 57.

45 Pivottally mounted upon one side of the frame 41 is a rocking lever 67, one end of which engages the reduced end of the enlarged head 65, and the other end of which is in engageable relation with a screw 68, one side of the head of which is flattened to provide a cam surface for imparting oscillatory movement to the lever 67 for the purpose of reciprocating the rod 63 for disengaging the pin 64 from the gear 57, or permitting

50 the engagement of these parts under the influence of the spring 66.

Under extraordinary conditions, it may be necessary to hand set the units, tens or hundredths wheels as well as the thousandths wheel and wheels of higher denomination. To permit the freeing of these wheels, the freeing of the shafts 35, 36 and 37 from the gears 21, 22 and 23, and the turning of these shafts incidental to the hand setting of the wheels actuated thereby, the

gears 38, 39 and 40 are idly mounted upon the shafts 35, 36 and 37, and connected therewith respectively by crown gears 69, 70 and 71, splined to the shafts 35, 36 and 37 respectively. These crown or clutch gears 69, 70 and 71 are actuated by means of nuts 72, 73 and 74 co-operating with screw threads upon the ends of the shafts 35, 36 and 37 respectively.

Slidably mounted upon the numbering head unit frame 41, adjacent the wheels 49, is a plate 75 having its opposite edges reduced, the width of this plate being such as to permit it to enter between the raised portions of the wheels 49 upon which the printing characters are engraved and hold these wheels against rotary movement. The plate 75 is normally locked in position by means of a set screw 76. If twin sets of digit wheels are used, the plate 75 will act in the same manner upon both sets of wheels.

While in a numbering head in which no transfer mechanisms are employed, and in which the mechanically actuated digit wheels are positively actuated, substantially all of the possibilities of a failure of the numbering head are avoided, nevertheless there is a possibility of the loss of alignment of the characters in excess of the permissible range, which is very small, due to wear of parts in the actuating mechanism.

To correct this condition, I provide the bridge 24 with an alining, registering or straightening device operative upon the various gears 52, 53, 61 and 62 which will, with each rotation of the cylinder 20 following the actuation of the four digit wheels of low denominations, correct any slight loss of alignment, and preferably hold the wheels against displacement, however minute, during the inking and the printing operations. The actuating means for this alining device forms a part of the numbering machine, and consists of a cam member concentric with the cylinder 20.

Specifically, the alining device comprises a slide 77, mounted in a slideway 78 formed in the bridge 24 directly below the vertical diameter of the sleeve 44. This slide has, through the opposite walls thereof, spaced cam slots 79, the slide being troughed, as shown more particularly in Fig. 13.

Seated in the slide 77 is a vertically reciprocating bar 80, having a slot 81 extending along the length thereof above the top of the slide 77, this bar being provided with studs 82 entering the cam slots 79 respectively. By this construction, the bar 80 may have vertical reciprocating movement imparted thereto by horizontal reciprocating movement of the slide 77.

Carried by the alining bar 80 within the frame 41 of each numbering head unit is a long straight tooth 83, conforming to and adapted to enter the alined spaces between

teeth upon the gears 52, 53, 61 and 62, so that if the teeth of any of these gears should be slightly out of alignment, the tooth 83 will correct this condition, and by properly positioning each of such gears, also properly position the digit wheels entrained therewith.

The tooth 83 is provided with a flange 84, adapted to enter the groove 81 in the bar 80, and an offset portion adapted to bring the tooth 83 directly above the slide 77 so as to avoid possible lateral play of the tooth. In fact, if desired, the ends of the tooth may be seated in suitable guideways in the frame 41.

It is desirable to so construct and arrange the straightening or alining bar and the teeth carried thereby, as to provide a yieldable support positioned between the tooth and said bar so as to avoid the necessity for any particular nicety in the adjustment of the actuating mechanism for said bar. This means, in the form of the invention shown, comprises a bowed spring 85 which will yield with excess movement of the bar 80 following the engagement of the tooth 83 with the gears.

Said bar 80 is provided at one end with a pendant arm 86, carrying an anti-friction roller 87, movable in a cam slot 88 in the fixed cam 89, which wheel is concentric with the cylinder 20. This cam slot is provided with a rise 90 and a fall 91 which are so positioned as to actuate the alining or straightening bar immediately following each impulse of the shafts 35, 36 or 37 so as to engage the teeth 83 with the gears with which they co-operate as to each numbering head unit, and maintain this relation during the inking and printing intervals, thereafter withdrawing said teeth from said gears preparatory to the next impulse of said shaft. The spring 85 is used merely to permit the teeth 83 to co-operate with the teeth upon the gears to the fullest possible extent while affording sufficient play to permit slight excess movement of the bar 80 without likelihood of injuring the gears.

In Figs. 1 and 2 of the drawings, the parts are shown at about one-half their actual size, except as to the thickness of the various gears co-operating with the various digit wheels, which in order to show dimensions are upon a slightly larger scale than in the actual numbering head units.

The various gears and the alining or straightening teeth are all hardened so as to minimize wear. The various digit wheels are of the usual construction. The construction and assembly of these parts requires extremely close work.

In assembling the numbering head units, great difficulty was experienced in properly locating the feather or spline connecting the various sleeves 42, 43 and 44 with the shafts 35, 36 and 37 within the allowed leeway, approximately three one-thousandths of an

inch. To correct this condition, I adjustably connect each sleeve 42—43—44 with its shaft by means of an adjustable coupling consisting of a collar, such as 92, 93 or 94, each having a feather 95 projecting into the keyway 76 of the shaft with which it co-operates, so as to be freely slideable longitudinally of said shaft. Carried by each sleeve is a collar 97 75 98 or 99. The co-operating collars are paired together.

One collar 92—93 or 94 of each pair is provided with diametrically opposite bearing shoulders such as 100 and 101, while the co-operating collar of each pair 95—96 or 97 carries two diametrically opposite set screws 102 and 103. The two collars of each pair having a swiveling relation, so that by loosening or tightening said screws, the sleeve carrying one of them, and the wheel or gear carried thereby, may be accurately adjusted circumferentially of the actuating shaft therefor, so as to bring the wheel carried or actuated thereby into proper alignment with the adjacent wheels.

While, primarily, this is an assembling operation, the screws 102 and 103 may be used to correct any loss of alignment of a digit wheel, due to any slight imperfections in the keyway in the actuating shaft for that sleeve. This last named condition may arise as a result of the adjustment of the numbering head unit in its entirety longitudinally of its actuating shaft.

The operation of the herein described numbering head is substantially as follows:—

Each of the numbering head units is independently assembled, the frames 41, to permit this assembling, being made in two parts connected by suitable screws in the usual manner. The shafts 35, 36 and 37 are mounted in the brackets 25 and 26, numbering units of the desired number being mounted upon said shafts before one of the end brackets, as 26, is connected with the bridge 24, of which it forms a part. The adjustment for spacing the various units is done after the bridge is mounted upon the cylinder 20. The shaft 35 passes through the sleeve 42 of all of the units of each bridge; the shaft 36 through all of the sleeves 43, and the shaft 37 through all of the sleeves 44, the feather 95, carried by each collar 92, 93 or 94, entering a keyway in the shaft with which it operates.

The head structure in its entirety is assembled on the bench, and any adjustment of the screws 102 and 103, necessary to properly line up the characters of the digit wheels of each unit, may be done upon the bench, or after the mounting of the head upon the cylinder 20.

When the head has been equipped with the desired number of units, it is mounted upon the cylinder 20 by tightening the screw rod 31 after the dogs 30 and 32 have been sepa-

rated and their bevelled edges positioned below the bevels 29 upon the cylinder 20. When a number of heads have been thus positioned upon the cylinder, they are severally adjusted circumferentially of the cylinder to secure a proper positioning of all heads upon the cylinder, and a proper spacing of the units of each head in relation to the others before tightening said screw rods. When so adjusting the head, the clutch gears 69, 70 and 71 may be disconnected from the gears 38, 39 and 40 so as to permit said gears to run idly about the machine actuated gears 21, 22 and 23 without actuating the digit wheels carried by, or positively actuated from, the shafts 35, 36 and 37.

When the digit wheels of each unit have been properly alined by means of the screws 102 and 103, if such alinement is required, the units of each numbering head properly spaced longitudinally of the cylinder 20, and the various heads properly spaced circumferentially of said cylinder, the machine is ready for a hand setting of the digit wheels of each unit preparatory to the beginning of a run of the numbering machine.

In adjusting the various units longitudinally of the cylinder 20, they slide freely along the shafts 35, 36 and 37. These shafts will vary in length according to the length of the cylinder 20 of the machine, which in turn is determined by the maximum width of sheet which the machine is required to accommodate.

With the shafts of the length ordinarily used, there may be slight deviation in the keyway cut in the shaft, from an absolutely true line, so that when the various units have been properly set, with relation to each other, some of the digit wheels may be slightly out of alinement through an imperfection in the keyway. The screws 102 and 103 may be used to correct this condition.

In setting the machine, it is always necessary to change the thousandths wheel of each unit, and it may be necessary to also change the units, tens and hundredths wheel and wheels of a denomination above the thousandths, according to the numbers to be printed. I will assume that all of the digit wheels thus require to be set.

The crown gears 69, 70 and 71, being disengaged from the gears 38, 39 and 40, the various shafts 35, 36 and 37 may be turned in relation to said gears 38, 39 and 40. The screw 68 is then turned so as to rock the lever 67, thus thrusting the rod 63 longitudinally of the sleeve 58 and disengaging the pin 64 from the gear 57, thus disconnecting the sleeve 58 from the shaft 37 and permitting the turning of said shaft or of said sleeve, one independently of the other. Thereafter, the shaft 35 may be turned to bring all of the units wheels actuated thereby to a position where, with the next actuation of the

machine, the desired digit will be brought into the printing position. The shafts 36 and 37 are similarly turned to bring the proper digit in the desired position as to the tens and the hundredths wheels respectively. The thousandths wheel is then turned by means of a hand pick. If high numbers are to be printed, the screw 76 may be released, and the plate 75 moved out of engaging relation with the digit wheels 49, and such of these wheels as are required for the desired setting of the unit, are turned by hand, and the plate 75 reset and locked in position by means of the screw 76, since none of the wheels 49 are turned during the operation of the numbering machine.

Assuming that the sheets to be numbered have ten-on, arranged in five rows of two each, the thousandths wheels of the units of all numbering heads will be differently set, so that upon the completion of the run of a thousand sheets, there will be no duplication of numbers, and yet there will be ten thousand consecutively numbered imprints. Prior to the succeeding run of a thousand sheets, it will be necessary for the operator to again change the thousandths and the tens of thousandths wheels as to all of the units upon all of the numbering heads on the machine.

It is for this reason that mechanisms permitting the rapid resetting, particularly of the thousandths wheels, are desirable, and that the automatic actuation of the tens of thousandths wheel is not necessary.

When the digit wheels have been properly set by hand, the screw 68 is turned in a reverse position, thus permitting the spring 66 to re-engage the pin 64 with the gear 57, and the various nuts 72, 73 and 74 are turned to engage the crown gears 69, 70 and 71 with the gears 38, 39 and 40 to couple these gears to the shafts 35, 36 and 37. The gears 69, 70 and 71 act in so setting the machine as to cause the transmission of power to the sleeves 42, 43 and 44 of all of the units embodied in a numbering head. The screws 68 and 76 are operative only as to each unit.

If it be desired to operate the numbering machine a number of times to properly ink the various digit wheels before beginning a run of the machine, the crown gears 69, 70 and 71 may be maintained out of engagement with the gears 38, 39 and 40 until this pre-inking operation has been completed.

As heretofore stated, the timing in the actuation of the shafts 35, 36 and 37 is controlled by mechanisms in the machine proper.

When the parts have been so set, the machine is ready for a run of a thousand sheets, or any multiple of a thousand sheets, according to the setting of the thousandths wheels.

The various units are secured in position upon the bridge 24 by means of the dovetailing between the frame 41 of each unit and said bridge, set screws also being used as to

each unit for locking it against movement longitudinally of the bridge.

As heretofore stated, the gears 21, 22 and 23 receive a timely actuation from mechanisms in the numbering machine. All of these gears rotate with the cylinder 20, and during this rotation, the shafts 35, 36 and 37 will not be turned, since the gears 38, 39 and 40, while enmeshed with the gears 21, 22 and 23, are turning therewith.

During each rotation of the cylinder 20, the gear 21 receives one impulse in excess of its turning movement with the cylinder 20, the length of this impulse being one tooth, so that as the gear 21 is thus turned, the shaft 35 will receive one-tenth of a revolution. The gear 22 receives a similar impulse upon each tenth revolution of the cylinder 20, and the gear 23 a similar impulse upon each one-hundredth revolution of the cylinder. Consequently the shafts 36 and 37 will receive one-tenth of a revolution, the former with each ten revolutions of the cylinder, and the latter with each one-hundred revolutions of the cylinder. Consequently, with each revolution of the cylinder 20, the units wheel of each digit wheel unit will be advanced one stage as a result of the rotation of the shaft 35 of each numbering head, since all of the numbering heads are simultaneously actuated, as to the units, tens or hundredths wheels, by the same gears 21, 22 and 23.

As the shaft 35 rotates, it will, as to each printing unit in each head, turn the sleeve 42 one-tenth of a revolution, and the units wheel 45 carried thereby to the same extent. This shaft has no influence whatever upon any of the other digit wheels of the various digit wheel units.

Upon each tenth revolution, the shaft 36 of each numbering head will turn the sleeves 43, of the various units of each numbering head, one-tenth of a revolution, the movement of this sleeve through the gear 51 and the intermediate gear 52, idly mounted upon the sleeve 44 and enmeshed with the gear 50 of the tens wheel 46, will impart one-tenth of a revolution to the tens wheel which is idly mounted upon the sleeve 42. The shaft 36 has absolutely no influence upon the action of any digit wheels excepting the tens wheel of the various units upon each numbering head.

Upon each one-hundredth revolution, the shaft 37 will impart to the sleeve 44, a one-tenth revolution, which movement, through the gears 53, enmeshed with the gears 50 of the digit wheel 47, will impart a one-tenth revolution to this wheel. The operation of the shaft 37, however, also serves to actuate the thousandths wheel of each digit wheel unit through the Geneva stop mechanism described, the sleeve 58 receiving one-tenth of a revolution with each ten revolutions of the shaft 37. Therefore, the shaft 37 acts through the gears 53 upon the hundredths wheel, and

through the Geneva stop movement upon the thousandths wheel, but the thousandths wheel is not actuated as a result of the turning of the hundredths wheel, but merely by a mechanism which does this turning; and through a mechanism, the Geneva stop movement, which has no influence whatever upon the operation of the hundredths wheel.

Each of the gear wheels 50, carried by the respective digit wheels of each unit 45, 46, 47 and 48, is enmeshed with a gear upon the sleeve 44, the gear 50 of the digit wheel 45 being enmeshed with the gear 62, the gear 50 of the tens wheel 46, with the gear 52, said gears 52 and 62 being idly mounted upon said shaft, the gears 50 of the hundredths wheel 47, with the gears 53 carried by and rotatable with said sleeve 44 and the gear 50 of the thousandths wheel 48 with the gear 61 idly mounted upon said sleeve 44. The teeth of the gears 52, 53, 61 and 62 are all accurately alined when the characters upon the digit wheels actuated thereby are accurately alined, so that these gears may be utilized to correct any slight variation in the rotary movement of the digit wheels, due to wear, or conditions akin to wear, upon the various gear wheels. The digit wheels upon all numbering heads which in their progressive actuation require to be turned during any revolution of the cylinder 20, are simultaneously turned, this turning movement occurring after the completion of the imprint by all of the numbering heads upon the sheet, and prior to the engagement of the various digit wheels with the inking mechanism of the numbering machine.

The rise 90 of the fixed cam 89 is so located as to be operative immediately following the impulse imparted to any of the gears 21, 22 and 23, while the fall 91 is so located as to be operative immediately following the completion of the impression upon the sheet being printed and preceding such an impulse.

With the position of parts as shown in Fig. 1, the numbering head therein shown is the first of a series of such heads upon the cylinder 20, the various gears 21, 22 and 23 having been just actuated to turn the various digit wheels requiring to be turned during that cycle of the operation of the machine.

With the continued rotation of the cylinder, the roller 87, shown in Fig. 1, will enter the rise 90, and the roller 87 of each succeeding numbering head as it reaches this position, will enter said rise. As said roller enters the rise 90, the slide 77 will be moved to the right, Fig. 1, in the slideway 78. The cam slots 79 in this slide acting upon the studs 82, carried by the bar 80, will move this bar toward the sleeve 44, thus moving the tooth 83 toward the sleeve 44 and into engagement with the teeth upon the gears 52, 53, 61 and 62 with a corrective effect in the event that any of the teeth of this gear be out

of alinement. It is obvious that any movement of the various gears above referred to will, through the gears 50, have a similar corrective effect upon the various digit wheels carrying these gears. Between the rise 90 and the fall 91, the tooth 83 will be held in this position, so that during the engagement of the various digit wheels with the inking rollers, and during the printing operation, 10 the tooth 83 will prevent any movement of the various digit wheels out of alinement.

As each numbering head leaves the printing position, the roller 87 carried by the slide 77 of that particular head, will enter the fall 15 91, thus imparting a reverse reciprocation to the slide 77 and a resultant downward movement of the bar 80 and of the teeth 83 carried thereby, thus disengaging said teeth from the gears 52, 53, 61 and 62 of each unit prior 20 to the next actuation of same and of the mechanically actuated digit wheels associated with said gears.

Twin printing units are used only when it is necessary to have the numbers fairly 25 close together, as in the case of coupon sheets, in which case all of the units will be set to a number corresponding with the bond to which the coupon sheet is attached. When so used, there may be an indefinite run of the 30 machine without resetting any of the digit wheels. When twin heads are used, the mode of operation is the same as with a single set of wheels, the sole difference being that the gear 51 has a digit wheel attached thereto, 35 and other digit wheels idly mounted upon the sleeve 43 carry gears enmeshed with the gears 52, 53, 61 and 62.

Whether a single or a twin set of printing 40 wheels is used, it is necessary that the printing characters be engraved upon the wheel in an order to correspond with the direction in which the wheel turns, since with the arrangement of gearing described, some of the 45 wheels will turn in one direction, while other wheels will turn in the other direction.

The construction of each of the units of a numbering head embodying the invention is such that there can be no cumulative error from a prolonged use of the head, since any 50 slight error, due to structural defects or wear, will be automatically corrected during each rotation of the cylinder 20.

A numbering head contains no springs upon 55 which the turning of the various digit wheels is dependent, all movements being positive and under power from the source driving the machine.

With a head embodying the invention 60 there is no possibility of duplication, skipping or any material overrunning of any of the wheels.

The head is capable of a wide range of adjustment, may be quickly mounted upon, and 65 removed from, the cylinder, and each head

may include a plurality of printing units accurately alined.

After each run of the machine, the various digit wheels, as required, may be rapidly 70 reset by hand.

The positive actuation of the various digit wheels of each unit of the numbering head permits the numbering machine to be operated at much higher speeds than is possible with spring actuated numbering heads, since 75 no inspection to detect failure of the numbering heads is required, and possibility of breakage of springs, or their failure to operate through inertia, is absent.

It is not my intention to limit the invention to the precise details of construction shown in the drawings, since such may be varied without departing from the spirit and scope of the invention.

Having described the invention, what I 85 claim as new and desire to have protected by Letters Patent, is:—

1. A numbering head embodying therein a bridge, means whereby said bridge may be mounted upon a numbering head cylinder, a plurality of shafts rotatably mounted in said bridge, gears carried by said shafts respectively, a numbering unit having a frame, a plurality of sleeves rotatably mounted in said frame, means whereby said sleeves are 90 each connected with a shaft, a plurality of digit wheels upon one of said sleeves, one of said digit wheels being rotatable with, and the others being rotatable independently of, said sleeve, gears carried by said independently rotatable wheels, and a gear carried by each of the other of said sleeves, entrained with a gear upon an independently rotatable wheel.

2. A numbering head embodying therein a bridge, means whereby said bridge may be mounted upon a numbering head cylinder, a plurality of shafts rotatably mounted in said bridge, gears carried by said shafts respectively, and a numbering unit having a frame, a plurality of sleeves rotatably mounted in said frame, said shafts respectively passing through a sleeve, means whereby said sleeves are each slidably and rotatably connected with a shaft, a plurality of digit wheels upon one of said sleeves, one of said digit wheels being rotatable with, and the others being rotatable independently of, said sleeve, gears carried by said independently rotatable wheels, and a gear carried by each of the other of said sleeves, entrained with a gear upon an independently rotatable wheel.

3. A numbering head embodying therein a bridge, means whereby said bridge may be 125 mounted upon a numbering head cylinder, three shafts rotatably mounted in said bridge, gears carried by said shafts respectively, and a numbering unit having a frame, three sleeves rotatably mounted in said 130

frame, means whereby said sleeves are each connected with a shaft, digit wheels including a units, a tens and a hundredths wheel upon one of said sleeves, one of said wheels being connected with said sleeve, and the others being idly mounted thereon, gears carried by said idly mounted wheels respectively, a gear train operating one of said idly mounted wheels, including a gear fixed to one 5 of said other sleeves, and an intermediate gear idly mounted upon the third sleeve enmeshed with the gear carried by said wheel, and a gear secured to the third sleeve enmeshed with the gear carried by the other 10 idly mounted wheel.

4. A numbering head embodying therein a bridge, means whereby said bridge may be mounted upon a numbering head cylinder, three shafts rotatably mounted in said 20 bridge, gears carried by said shafts respectively, and a numbering unit having a frame, three sleeves rotatably mounted in said frame, means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels 25 respectively, a gear train operating said tens wheel, including a gear fixed to one of said other sleeves, and an intermediate gear idly mounted upon the third sleeve enmeshed with the gear carried by said tens wheel, a gear secured to the third sleeve enmeshed with the gear carried by the hundredths wheel, and a gear train between the shaft connected with the sleeve carrying the gear operating the hundredths wheel and the thousandths wheel for imparting a timely 35 actuation to said thousandths wheel.

5. A numbering head embodying therein a bridge, means whereby said bridge may be mounted upon a numbering head cylinder, three shafts rotatably mounted in said bridge, gears carried by said shafts respectively, and a numbering unit having a frame, three sleeves rotatably mounted in said frame, means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear train operating said tens wheel, including a gear fixed to one of said other sleeves, and an intermediate gear idly mounted upon the third sleeve enmeshed with the gear carried by said tens wheel, a gear secured to the third sleeve enmeshed with the gear carried by the hundredths wheel, a thousandths wheel actuating shaft rotatably mounted in said frame, a gear carried thereby, an intermediate gear idly mounted upon the sleeve carrying the gear operating the hundredths wheel, and enmeshed with the gear carried by the thousandths wheel, and a Geneva stop movement, the driving gear of which is carried by the shaft with which the sleeve carrying the gear operating the hundredths wheel is connected, and the driven 55 by, an intermediate gear idly mounted upon

the sleeve carrying the gear operating the hundredths wheel, and enmeshed with the gear carried by the thousandths wheel, and a Geneva stop movement, the driving gear of which is carried by the shaft with which the sleeve carrying the gear operating the hundredths wheel is connected, and the driven gear of which is carried by said thousandths wheel actuating shaft. 70

6. A numbering head embodying therein a bridge, means whereby said bridge may be mounted upon a numbering head cylinder, three shafts rotatably mounted in said bridge, gears carried by said shafts respectively, and a numbering unit having a frame, three sleeves rotatably mounted in said frame through which said shafts respectively pass, means whereby said sleeves are each slidably and rotatably connected with a shaft, digit wheels including a units, a tens and a hundredths wheel upon one of said sleeves, one of said wheels being connected with said sleeve, and the others being idly mounted thereon, gears carried by said idly mounted wheels respectively, a gear train operating one of said idly mounted wheels, including a gear fixed to one of said other sleeves, and an intermediate gear idly mounted upon the third sleeve enmeshed with the gear carried by said wheel, and a gear secured to the third sleeve enmeshed with the gear carried by the other idly mounted wheel. 80 85 90 95

7. A numbering head embodying therein a bridge, means whereby said bridge may be mounted upon a numbering head cylinder, three shafts rotatably mounted in said bridge, gears carried by said shafts respectively, and a numbering unit having a frame, three sleeves rotatably mounted in said frame through which said shafts respectively pass, means whereby said sleeves are each slidably 100

and rotatably connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear train operating said tens wheel, including a gear fixed to one 105

of said other sleeves, and an intermediate gear idly mounted upon the third sleeve enmeshed with the gear carried by said tens wheel, a gear secured to the third sleeve enmeshed with the gear carried by the hundredths wheel, a thousandths wheel actuating shaft rotatably mounted in said frame, a gear carried thereby, an intermediate gear idly mounted upon the sleeve carrying the gear operating the hundredths wheel, and enmeshed with the gear carried by the thousandths wheel, and a Geneva stop movement, the driving gear of which is carried by the shaft with which the sleeve carrying the gear operating the hundredths wheel is connected, and the driven 110

120 125 130

gear of which is carried by said thousandths wheel actuating shaft.

8. A numbering head embodying therein a bridge, means whereby said bridge may be mounted upon a numbering head cylinder, three shafts rotatably mounted in said bridge, gears carried by said shafts respectively, and a numbering unit having a frame, three sleeves rotatably mounted in said frame, 5 means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear train operating said tens wheel, including a gear fixed to one of said other sleeves, and an intermediate gear idly mounted upon the 10 third sleeve enmeshed with the gear carried by said tens wheel, a gear secured to the third sleeve enmeshed with the gear carried by the hundredths wheel, a gear train between the shaft connected with the sleeve carrying the gear operating the hundredths wheel and the thousandths wheel for imparting a timely actuation to said thousandths wheel, and means whereby said gear train may be made inoperative to transmit power from said shaft to said 15 thousandths wheel.

9. A numbering head embodying therein a bridge, means whereby said bridge may be mounted upon a numbering head cylinder, three shafts rotatably mounted in said bridge, 20 gears carried by said shafts respectively, and a numbering unit having a frame, three sleeves rotatably mounted in said frame, means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear 25 train operating said tens wheel, including a gear fixed to one of said other sleeves, and an intermediate gear idly mounted upon the third sleeve enmeshed with the gear carried by said tens wheel, a gear secured to the third sleeve 30 enmeshed with the gear carried by the hundredths wheel, a thousandths wheel actuating means comprising a hollow shaft rotatably mounted in said frame, a gear carried thereby, an intermediate gear idly mounted upon a sleeve carrying the gear operating the hundredths wheel and the thousandths wheel for imparting a timely 35 actuation to said thousandths wheel, and means whereby said gear train may be made inoperative to transmit power from said shaft to said thousandths wheel.

40 carrying the gear operating the hundredths wheel is connected, and a driven gear idly mounted upon said hollow shaft, a clutch member slidably mounted on said hollow shaft, a rod slidably mounted in said hollow shaft, a clutch member carried by said rod and rotatable with

said shaft, clutch members co-operating therewith carried by said driven gear, a rocking lever carried by said frame in operative relation to said rod, and a manually operative cam member mounted upon said frame and engaging said lever, whereby said Geneva stop movement may be made inoperative to transmit power to permit the hand setting of the thousandths wheel.

10. A numbering head embodying therein a bridge, means whereby said bridge may be mounted upon a numbering head cylinder, a plurality of shafts rotatably mounted in said bridge, gears idly mounted upon said shafts respectively, a releasable clutch mechanism whereby each of said gears may be connected with its shaft, and a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, said sleeve, gears carried by said independently rotatable wheels, and a gear carried by each of the other of said sleeves, entrained with a gear upon an independently rotatable wheel.

11. A numbering head embodying therein a bridge, means whereby said bridge may be mounted upon a numbering head cylinder, three shafts rotatably mounted in said bridge, gears idly mounted upon said shafts respectively, a releasable clutch mechanism whereby each of said gears may be connected with its shaft, and a numbering unit having a frame, three sleeves rotatably mounted in said frame, means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear train operating said tens wheel, including a gear fixed to one of said other sleeves, and an intermediate gear idly mounted upon the third sleeve enmeshed with the gear carried by said tens wheel, a gear secured to the third sleeve 105 enmeshed with the gear carried by the hundredths wheel, a thousandths wheel actuating means comprising a hollow shaft rotatably mounted in said frame, a gear carried thereby, an intermediate gear idly mounted upon a sleeve carrying the gear operating the hundredths wheel and the thousandths wheel for imparting a timely 110 actuation to said thousandths wheel, and means whereby said gear train may be made inoperative to transmit power from said shaft to said thousandths wheel.

12. A numbering head embodying therein a bridge, means whereby said bridge may be mounted upon a numbering head cylinder, three shafts rotatably mounted in said bridge, gears idly mounted upon said shafts respectively, a releasable clutch mechanism 115

- whereby each of said gears may be connected with its shaft, and a numbering unit having a frame, three sleeves rotatably mounted in said frame, means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear train operating said tens wheel, including a gear fixed to one of said other sleeves, and an intermediate gear idly mounted upon the third sleeve enmeshed with the gear carried by said tens wheel, a gear secured to the third sleeve enmeshed with the gear carried by the hundredths wheel, a thousandths wheel actuating means comprising a hollow shaft rotatably mounted in said frame, a gear carried thereby, an intermediate gear idly mounted upon a sleeve carrying the gear operating the hundredths wheel and enmeshed with the gear carried by the thousandths wheel, a Geneva stop movement including a driving gear carried by the shaft with which the sleeve carrying the gear operating the hundredths wheel is connected, and a driven gear idly mounted upon said hollow shaft, a clutch member slidably mounted on said hollow shaft, a rod slidably mounted in said hollow shaft, a clutch member carried by said rod and rotatable with said shaft, clutch members co-operating therewith carried by said driven gear, a rocking lever carried by said frame in operative relation to said rod, and a manually operative cam member mounted upon said frame and engaging said lever, whereby said Geneva stop movement may be made inoperative to transmit power to permit the hand setting of the thousandths wheel.
13. A numbering head embodying therein a bridge, means whereby said bridge may be mounted upon a numbering head cylinder, a plurality of shafts rotatably mounted in said bridge, gears carried by said shafts respectively, and a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, said sleeve, gears carried by said digit wheels respectively, gears carried by another of said sleeves, one of which is connected with said sleeve, and the others of which are idly mounted thereon, said gears being enmeshed with the gears upon said digit wheels respectively, a gear carried by the third sleeve enmeshed with one of said idly mounted gears, a straight tooth movable in said frame and engageable with the several gears carried by or idly mounted upon one of said sleeves, a slide mounted upon said bridge, a straightening bar operative upon said tooth, co-operating means carried by said slide and said straightening bar, whereby with reciprocatory movement of said slide, said bar will be moved toward and from said gears to engage and disengage said tooth and said gears, and means whereby reciprocatory movement may be imparted to said slide.
14. A numbering head embodying therein a bridge, means whereby said bridge may be mounted upon a numbering head cylinder, a plurality of shafts rotatably mounted in said bridge, gears carried by said shafts respectively, and a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, said sleeve, gears carried by said digit wheels respectively, gears carried by another of said sleeves, one of which is connected with said sleeve, and the others of which are idly mounted thereon, said gears being enmeshed with the gears upon said digit wheels respectively, a gear carried by the third sleeve enmeshed with one of said idly mounted gears, a straight tooth movable in said frame and engageable with the several gears carried by or idly mounted upon one of said sleeves, a slide mounted upon said bridge, a straightening bar operative upon said tooth, co-operating means carried by said slide and said straightening bar, whereby with reciprocatory movement of said slide, said bar will be moved toward and from said gears to engage and disengage said tooth and said gears, and means whereby reciprocatory movement may be imparted to said slide.
15. A numbering head embodying therein a bridge, means whereby said bridge may be mounted upon a numbering head cylinder, a plurality of shafts rotatably mounted in said bridge, gears carried by said shafts respectively, and a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, said sleeve, gears carried by said digit wheels respectively, gears carried by another of said sleeves, one of which is connected with said sleeve, and the others of which are idly mounted thereon, said gears being enmeshed with the gears upon said digit wheels respectively, a gear carried by the third sleeve enmeshed with one of said idly mounted gears, a straight tooth movable in said frame and engageable with the several gears carried by or idly mounted upon one of said sleeves, a slide mounted upon said bridge, a straightening bar having a slot extending longitudinally thereof, said tooth having a flange entering said slot whereby it may slide along said bar, co-operating means carried by said slide and said straightening bar, whereby with reciprocatory movement of said slide, said bar will be moved toward and from said gears to engage and disengage said tooth and said gears, and means whereby reciprocatory movement may be imparted to said slide.

catory movement of said slide, said bar will be moved toward and from said gears to engage and disengage said tooth and said gears, and means whereby reciprocatory movement 5 may be imparted to said slide.

16. A numbering head embodying therein a bridge, means whereby said bridge may be mounted upon a numbering head cylinder, a plurality of shafts rotatably mounted in said 10 bridge, gears carried by said shafts respectively, and a numbering unit having a frame, a plurality of sleeves rotatably mounted in said frame, means whereby said sleeves are each connected with a shaft, a plurality of digit 15 wheels upon one of said sleeves, one of said digit wheels being rotatable with, and the others being rotatable independently of, said sleeve, gears carried by said digit wheels respectively, gears carried by another of said 20 sleeves, one of which is connected with said sleeve, and the others of which are idly mounted thereon, said gears being enmeshed with the gears upon said digit wheels respectively, a gear carried by the third sleeve enmeshed 25 with one of said idly mounted gears, a straight tooth movable in said frame and engageable with the several gears carried by or idly mounted upon one of said sleeves, a slide mounted upon said bridge, a straightening 30 bar having a slot extending longitudinally thereof, said tooth having a flange entering said slot whereby it may slide along said bar, yieldable means positioned between said tooth and said bar, co-operating means carried 35 by said slide and said straightening bar, whereby with reciprocatory movement of said slide, said bar will be moved toward and from said gears to engage and disengage said tooth and said gears, and means whereby reciprocatory 40 movement may be imparted to said slide.

17. A numbering head embodying therein a bridge, means whereby said bridge may be mounted upon a numbering head cylinder, 45 three shafts rotatably mounted in said bridge, gears carried by said shafts respectively, and a numbering unit having a frame, three sleeves rotatably mounted in said frame, means whereby said sleeves are each connected with a shaft, digit wheels including a units, a tens, a hundredths and a thousandths 50 wheel and a plurality of wheels of higher denomination upon one of said sleeves, the units wheel being connected with said sleeve, and the others being idly mounted thereon, gears carried by said idly mounted wheels, other than said wheels of higher denomination, respectively, a gear train operating said tens wheel, including a gear fixed to one of 55 said other sleeves, and an intermediate gear idly mounted upon the third sleeve enmeshed with the gear carried by said tens wheel, a gear secured to the third sleeve enmeshed with the gear carried by the hundredths wheel, a gear train between the shaft connected with the sleeve carrying the gear operating the hundredths wheel and the thousandths wheel for 60 imparting a timely actuation to said thousandths wheel, means whereby said gear train may be made inoperative to transmit power from said shaft to said thousandths wheel, a slide engageable with said wheels of higher denomination, and means permitting movement of said slide to permit the hand turning of said wheels.

18. A numbering head embodying therein a bridge, means whereby said bridge may be mounted upon a numbering head cylinder, three shafts rotatably mounted in said bridge, gears carried by said shafts respectively, and a numbering unit having a frame, three sleeves rotatably mounted in said frame, means whereby said sleeves are each connected with a shaft, digit wheels including a units, a tens, a hundredths and a thousandths wheel and a plurality of wheels of higher denomination upon one of said sleeves, the units wheel being connected with said sleeve, and the others being idly mounted thereon, gears carried by said idly mounted wheels, other than said wheels of higher denomination, respectively, a gear train operating said tens wheel, including a gear fixed to one of said other sleeves, and an intermediate gear idly mounted upon the third sleeve enmeshed with the gear carried by said tens wheel, a gear secured to the third sleeve enmeshed with the gear carried by the hundredths wheel, a gear train between the shaft connected with the sleeve carrying the gear operating the hundredths wheel and the thousandths wheel for 70 imparting a timely actuation to said thousandths wheel, means whereby said gear train may be made inoperative to transmit power from said shaft to said thousandths wheel, a slide engageable with said wheels of higher denomination, and means permitting movement of said slide to permit the hand turning of said wheels.

19. A numbering head embodying therein a bridge, means whereby said bridge may be mounted upon a numbering head cylinder, a plurality of shafts rotatably mounted in said bridge, gears idly mounted upon said shafts respectively, a releasable clutch mechanism whereby each of said gears may be connected with its shaft, and a numbering unit having a frame, a plurality of sleeves rotatably mounted in said frame, means whereby said sleeves are each connected with a shaft, a plurality of digit wheels upon one of said sleeves, the digit wheels of lower denomination being positively driven, and the wheels of higher denomination being only manually operative, one of said digit wheels of lower denomination being rotatable with, and the others of lower denomination being rotatable independently of, said sleeve, gears carried by said independently rotatable wheels, a gear carried by each of the other of said sleeves, entrained with a gear upon an inde- 75 80 85 90 95 100 105 110 115 120 125 130

19. A numbering head embodying therein a bridge, means whereby said bridge may be mounted upon a numbering head cylinder, a plurality of shafts rotatably mounted in said bridge, gears idly mounted upon said shafts respectively, a releasable clutch mechanism whereby each of said gears may be connected with its shaft, and a numbering unit having a frame, a plurality of sleeves rotatably mounted in said frame, means whereby said sleeves are each connected with a shaft, a plurality of digit wheels upon one of said sleeves, the digit wheels of lower denomination being positively driven, and the wheels of higher denomination being only manually operative, one of said digit wheels of lower denomination being rotatable with, and the others of lower denomination being rotatable independently of, said sleeve, gears carried by said independently rotatable wheels, a gear carried by each of the other of said sleeves, entrained with a gear upon an inde- 75 80 85 90 95 100 105 110 115 120 125 130

pendently rotatable wheel, a slide engageable with said wheels of higher denomination, and means permitting movement of said slide to permit the hand turning of said 5 wheels.

20. A numbering head embodying therein a bridge, means whereby said bridge may be mounted upon a numbering head cylinder, three shafts rotatably mounted in said bridge, 10 gears idly mounted upon said shafts respectively, a releasable clutch mechanism whereby each of said gears may be connected with its shaft, and a numbering unit having a frame, three sleeves rotatably mounted in 15 said frame, means whereby said sleeves are each connected with a shaft, digit wheels including a units, a tens, a hundredths and a thousandths wheel and a plurality of wheels of higher denomination upon one of said 20 sleeves, the units wheel being connected with said sleeve, and the others being idly mounted thereon, gears carried by said idly mounted wheels, other than said wheels of higher denomination, respectively, a gear train operating said tens wheel, including a gear fixed to one of said other sleeves, and an intermediate gear idly mounted upon the third sleeve enmeshed with the gear carried by said tens wheel, a gear secured to the third sleeve enmeshed with the gear carried by the hundredths wheel, a gear train between the shaft connected with the sleeve carrying the gear operating the hundredths wheel and the thousandths wheel for imparting a timely actuation 25 to said thousandths wheel, means whereby said gear train may be made inoperative to transmit power from said shaft to said thousandths wheel, a slide engageable with said wheels of higher denomination, and 30 means permitting movement of said slide to permit the hand turning of said wheels.

21. A numbering head embodying therein a bridge, means whereby said bridge may be mounted upon a numbering head cylinder, a 45 plurality of shafts rotatably mounted in said bridge, gears carried by said shafts respectively, and a plurality of numbering units adjustably mounted upon said bridge and in relation to each other, each having a frame, 50 a plurality of sleeves rotatably mounted in said frame, said shafts respectively passing through a sleeve, means whereby said sleeves are each slidably and rotatably connected with a shaft, a plurality of digit wheels upon 55 one of said sleeves, one of said digit wheels being rotatable with, and the others being rotatable independently of, said sleeve, gears carried by said independently rotatable wheels, and a gear carried by each of the 60 other of said sleeves, entrained with a gear upon an independently rotatable wheel.

22. A numbering head embodying therein a bridge, means whereby said bridge may be mounted upon a numbering head cylinder, 65 three shafts rotatably mounted in said bridge,

gears carried by said shafts respectively, and a plurality of numbering units adjustably mounted upon said bridge and in relation to each other, each having a frame, three sleeves rotatably mounted in said frame, means 70 whereby said sleeves are each connected with a shaft, digit wheels including a units, a tens and a hundredths wheel upon one of said sleeves, one of said wheels being connected with said sleeve, and the others being idly 75 mounted thereon, gears carried by said idly mounted wheels respectively, a gear train operating one of said idly mounted wheels, including a gear fixed to one of said other sleeves, and an intermediate gear idly mounted upon the third sleeve enmeshed with the gear carried by said wheel, and a gear secured to the third sleeve enmeshed with the gear carried by the other idly mounted wheel.

23. A numbering head embodying therein a bridge, means whereby said bridge may be mounted upon a numbering head cylinder, three shafts rotatably mounted in said bridge, gears carried by said shafts respectively, and a plurality of numbering units adjustably 80 mounted upon said bridge and in relation to each other, each having a frame, three sleeves rotatably mounted in said frame, means whereby said sleeves are each connected with a shaft, digit wheels including a units, a tens, a hundredths and a thousandths wheel upon one of said sleeves, the units wheel being connected with said sleeve, and the others being idly mounted thereon, gears carried by said idly mounted wheels respectively, a gear 85 train operating said tens wheel, including a gear fixed to one of said other sleeves, and an intermediate gear idly mounted upon the third sleeve enmeshed with the gear carried by said tens wheel, a gear secured to the third sleeve enmeshed with the gear carried by the hundredths wheel, a thousandths wheel actuating shaft rotatably mounted in said frame, a gear carried thereby, an intermediate gear idly mounted upon the sleeve carrying the 90 gear operating the hundredths wheel, and enmeshed with the gear carried by the thousandths wheel, and a Geneva stop movement, the driving gear of which is carried by the shaft with which the sleeve carrying the gear operating the hundredths wheel is connected, and the driven gear of which is carried by said thousandths wheel actuating shaft.

24. A numbering head embodying therein a bridge, means whereby said bridge may be mounted upon a numbering head cylinder, a plurality of shafts rotatably mounted in said bridge, gears carried by said shafts respectively, a plurality of numbering units adjustably mounted upon said bridge and in relation to each other, each having a frame, a plurality of sleeves rotatably mounted in said frame, means whereby said sleeves are each connected with a shaft, a plurality of digit 120 wheels

wheels upon one of said sleeves, one of said digit wheels being rotatable with, and the others being rotatable independently of, said sleeve, gears carried by said digit wheels respectively, 5 gears carried by another of said sleeves, one of which is connected with said sleeve, and the others of which are idly mounted thereon, said gears being enmeshed with the gears upon said digit wheels respectively, 10 a gear carried by the third sleeve enmeshed with one of said idly mounted gears, and a straight tooth movable in said frame and engageable with the several gears carried by or idly mounted upon one of said sleeves, a slide 15 mounted upon said bridge, a straightening bar having a slot extending longitudinally thereof adjacent all of said units, said teeth respectively having a flange entering a slot whereby said teeth may slide along said bar, 20 co-operating means carried by said slide and said straightening bar, whereby with reciprocatory movement of said slide, said bar will be moved toward and from said gears to engage and disengage said tooth and said gears, 25 and means whereby reciprocatory movement may be imparted to said slide.

25. A numbering head embodying therein a bridge, means whereby said bridge may be mounted upon a numbering head cylinder, 30 three shafts rotatably mounted in said bridge, gears idly mounted upon said shafts respectively, a releasable clutch mechanism whereby each of said gears may be connected with its shaft, a plurality of numbering units adjustably mounted upon said bridge and in relation to each other, each having a frame, three sleeves rotatably mounted in said frame, means whereby said sleeves are each connected with a shaft, digit wheels including a units, 35 a tens, a hundredths and a thousandths wheel and a plurality of wheels of higher denomination upon one of said sleeves, the units wheel being connected with said sleeve, and the others being idly mounted thereon, gears carried by said idly mounted wheels, other than 40 said wheels of higher denomination, respectively, a gear train operating said tens wheel, including a gear fixed to one of said other sleeves, and an intermediate gear idly mounted upon the third sleeve enmeshed with the 45 gear carried by said tens wheel, a gear secured to the third sleeve enmeshed with the gear carried by the hundredths wheel, a gear train between the shaft connected with the 50 sleeve carrying the gear operating the hundredths wheel and the thousandths wheel for imparting a timely actuation to said thousandths wheel, means whereby said gear train may be made inoperative to transmit 55 power from said shaft to said thousandths wheel, a slide engageable with said wheels of higher denomination, and means permitting movement of said slide to permit the hand turning of said wheels.

65 26. A numbering head embodying therein

a bridge, means whereby said bridge may be mounted upon a numbering head cylinder, a plurality of shafts rotatably mounted in said bridge, gears carried by said shafts respectively, and a numbering unit having a frame, 70 a plurality of sleeves rotatably mounted in said frame, means whereby said sleeves are each connected with a shaft, including therein co-operating members whereby said sleeves may be adjusted circumferentially of their respective shafts, a plurality of digit wheels upon one of said sleeves, one of said digit wheels being rotatable with, and the others being rotatable independently of, said sleeve, 75 gears carried by said independently rotatable wheels, and a gear carried by each of the other of said sleeves, entrained with a gear upon an independently rotatable wheel.

27. A numbering head embodying therein a bridge, means whereby said bridge may be mounted upon a numbering head cylinder, a plurality of shafts rotatably mounted in said bridge, gears carried by said shafts respectively, and a numbering unit having a frame, 80 a plurality of sleeves rotatably mounted in said frame, a collar, co-operating means upon said shaft and upon said collar whereby said collar may be adjusted longitudinally of said shaft and will be rotatable therewith, a second collar carried by the sleeve and rotatable in relation to said first named collar, said collars being provided with registering opposed shoulders, set screws projecting beyond the shoulders of one of said collars into engaging 85 relation with the shoulders upon the other of said collars, whereby said sleeves may be adjusted circumferentially of said shafts, a plurality of digit wheels upon one of said sleeves, one of said digit wheels being rotatable with, and the others being rotatable independently of, 90 said sleeve, gears carried by said independently rotatable wheels, and a gear carried by each of the other of said sleeves, entrained with a gear upon an independently rotatable wheel.

28. A numbering head embodying therein a bridge, bevelled dogs slidably mounted adjacent the opposite ends of said bridge, a screw threaded rod engaging a screw threaded opening in one of said dogs and passing through the other of said dogs, a collar fixed to said rod engaging the other of said dogs, whereby said bridge may be mounted upon, or removed from, a numbering head cylinder, a plurality of shafts rotatably mounted in said bridge, gears carried by said shafts respectively, and a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, 100 said sleeve, gears carried by said independently rotatable wheel.

105 29. A numbering head embodying therein a bridge, a screw threaded rod passing through the bridge, a screw threaded opening in one of the ends of the bridge, a collar fixed to the rod engaging the other end of the bridge, whereby the bridge may be mounted upon, or removed from, a numbering head cylinder, a plurality of shafts rotatably mounted in said bridge, gears carried by said shafts respectively, and a numbering unit having a frame, a plurality of sleeves rotatably mounted in said frame, means whereby said sleeves are each connected with a shaft, a plurality of digit wheels upon one of said sleeves, one of said digit wheels being rotatable with, and the others being rotatable independently of, 110 said sleeve, gears carried by said independently rotatable wheel.

ently rotatable wheels, and a gear carried by each of the other of said sleeves, entrained with a gear upon an independently rotatable wheel.

5 29. A numbering head embodying therein a bridge, means whereby said bridge may be mounted upon a numbering head cylinder, a plurality of shafts rotatably mounted in said bridge, gears carried by said shafts respectively, and a numbering unit having a frame, a plurality of sleeves rotatably mounted in said frame, means whereby said sleeves are each connected with a shaft, two sets of digit wheels consisting of a plurality of digit wheels respectively, one set of digit wheels being upon one sleeve, and the other set upon another sleeve, one of said digit wheels of each set being rotatable with, and the others being rotatable independently of, its 10 sleeve, gears carried by the wheels of each set, and gears carried by another of said sleeves, entrained with the gears upon the wheels of the same denomination of each set, one of said last named gears being carried by 15 its sleeve, and the other of said last named gears being idly mounted on said sleeve.

30. A numbering head embodying therein a bridge, means whereby said bridge may be mounted upon a numbering head cylinder, 30 three shafts rotatably mounted in said bridge, gears idly mounted upon said shafts respectively, a releasable clutch mechanism whereby each of said gears may be connected with its shaft, and a numbering unit having a frame, three sleeves rotatably mounted in said frame, means whereby said sleeves are each connected with a shaft, two sets of digit wheels each including a units, a tens, a hundredths and a thousandths wheel and a plurality of wheels of higher denomination, the 35 wheels of each set being mounted upon a sleeve, the units wheel of one set being connected with its sleeve, and the others being idly mounted thereon, and the tens wheel of 40 another set being connected with its sleeve, and the others being idly mounted thereon, gears carried by the wheels of each set, other than said wheels of higher denomination, respectively, gears mounted upon the remaining 45 45 sleeve enmeshed with the gears upon the corresponding wheels of each set respectively, said intermediate gear operative upon the hundredths wheel being secured to, and rotatable with, its sleeve, a gear train between the 50 shaft connected with the sleeve carrying the gear operating the hundredths wheel and the thousandths wheel, including a gear idly mounted upon said third sleeve for imparting a timely actuation to said thousandths 55 wheel, means whereby said gear train may be made inoperative to transmit power from said shaft to said thousandths wheel, a slide engageable with said wheels of higher denomination of each set, and means permitting 60

movement of said slide to permit the hand turning of said wheels.

In witness whereof I have hereunto affixed my signature, this 18th day of December, 1928.

JAMES H. REINHARDT.
